UNITED STATES PATENT OFFICE.

EDWARD A. TUTTLE, OF NEW YORK, N. Y., ASSIGNOR TO "THE TUTTLE AND BAILEY MANUFACTURING COMPANY," OF SAME PLACE.

DESIGN FOR A HOT-AIR REGISTER.

Specification forming part of Design No. 5,934, dated June 11, 1872.

Specification describing a new and original Design for Circular Register, invented by EDWARD A. TUTTLE, of the city, county, and State of New York.

The accompanying photograph fully represents my new invention.

This invention relates to a new design for circular registers for hot-air and other flues. The design shows a circular center with beaded outline and embracing a cross. From outwardly-projecting arms of the circle extends a series of crosiers, crossing each other in pairs, and reaching nearly to the border of the reg-

ister. Guirlands connect the hooks of the crosiers in pairs. The staffs of every intersecting pair of crosiers are embraced by the flukes of an anchor, whose arms project from a reticulated segmental ornament that extends to the circular border of the register.

I claim as my invention—

The design for a register, as shown.

EDWARD A. TUTTLE.
